4 Claims

ABSTRACT OF THE DISCLOSURE

An undergarment which serves as brassiere, and/or stocking support, and which also serves as a bracer or support for the back of the wearer.

THE INVENTION

The undergarment includes breast-supporting cups, a bodice, or a combined bodice and waist which can be worn with, or as a replacement for, a conventional girdle and with or without stocking supports.

In the drawings:

FIG. 1 is a front perspective view of an undergarment constructed according to one embodiment of the invention.

FIG. 2 is a rear perspective view of the same.

FIG. 3 is a front perspective view showing how the garment looks when in use.

FIG. 4 is a front perspective view showing a garment the bodice of which includes a separable bottom portion.

In a preferred embodiment the garment includes shoulder straps 10 which connect the upper edge of the front of the bodice to the upper edge of the back panel 24 thereof and which are wide enough to cover the major portion of the shoulders between the junction of the arm and the neck. This distributes the weight, or downward pressure exerted on the shoulders and prevents the soreness, the discolorations, and the ridges which result from the use of narrow shoulder straps of the order of one or two inches in width. The garment is also provided with armholes of which engage the uppermost portions of the arms and prevent "creeping" of the straps toward the neck.

At its front, the garment is provided with breast cups 12 which are constructed to support and point the breasts upwardly. The breast cups are carried by, or form part of an abbreviated bodice 14 which is slit down the center and the edges 16 of which are drawn and held together by a conventional slide fastener 18. It will be noted that the back panel 24 of the bodice is extended downwardly so as to overlie the small of the back of the wearer. Side gussets 20 and a back gusset 22 are provided for limited adjustment.

The back 24 is provided with two strap-like members 26 which preferably, but not necessarily, extend from a point near the shoulders to a point below the bottom edge 30 of the garment. In any event, the straps are provided with hooks or clasps 28 for directly engaging the tops of the stocking or for engaging separate straps 30, such as those shown in FIG. 7, which engage the stocking tops.

When a garment so constructed is worn, and the slide fastener is closed, the bodice tightly hugs the torso below the breasts while the breast cups enclose the breasts. This firmly fixes the position of the garment relative to the

2

body, so that any downward pull on the back of the garment, by the straps 26, or otherwise, will exert a backward pull on the shoulders of the wearer and results in a more erect posture. Also, downward pull on the straps presses the back of the garment against the back of the wearer and provides very helpful support. The downward pull referred to is supplied by engaging the straps 26 with the stockings or with the upper edge of a girdle. When the garment is used with a girdle, the straps can be shortened, or appropriate clasps can be secured directly to the bottom edge of the garment back for engagement with the top edge of the girdle.

It will be noted that, when worn as shown in FIG. 3, the garment gives support to the back but leaves the abdomen exposed and free. This permits free movement of the diaphragm and permits deep breathing which is essential to well-being. This is especially useful for persons who are obese or who have prominent abdomens.

FIG. 7 shows an undergarment, the shoulder panels 34 of which are cut on a wide angle and are somewhat narrow, for evening wear.

FIG. 8 shows the garment which is produced when the front panel below the broken line in FIG. 7 is removed.

As can be seen from the drawings, the breast cups are built into the bodice, the meeting edges of which are joined by slide fastener 18. By this arrangement, the V-cut formed by the edges 30 of the panels is extended downwardly and provides a distinct separation or cleavage of the breasts with the joined edges abutting the sternum. In practice, this has proved to be a great improvement over the wire brassieres which were designed to effect this separation, and which caused discomfort and irritation to the wearer.

What I claim is:

1. A ladies' undergarment comprising front, back and sides, co-acting to form a bodice which tightly hugs the torso below the breasts of the wearer,

breast-support cups separately secured to said bodice, shoulder straps connecting the front of the bodice to the back thereof,

said shoulder straps being of a width to cover the major portion of the shoulders measured from the neck toward the arm, and

supports carried by the back of said bodice.

2. The garment of claim 1 wherein the outer edges of said straps also engage the adjacent upper portions of the arms to prevent the straps from creeping toward the neck.

3. The garment of claim 1 wherein the bodice includes a lower portion which is attachable to, and detachable from, the lower edge of the bodice, at will.

4. The garment of claim 1 wherein the bottom edge of the back is longer, vertically measured than the front thereof.
